UNITED STATES PATENT OFFICE.

GEORGE STENINGER BOLLENSSEN, OF CHICAGO, ILLINOIS, ASSIGNOR TO FELT & TARRANT MANUFACTURING COMPANY, OF CHICAGO, ILLINOIS, A CORPORATION OF ILLINOIS.

ADDING-MACHINE.

1,074,689.

Specification of Letters Patent.

Patented Oct. 7, 1913.

Application filed September 30, 1912. Serial No. 723,025.

To all whom it may concern:

Be it known that I, GEORGE S. BOLLENSSEN, a citizen of the United States, residing in Chicago, in the county of Cook and State of Illinois, have invented a new and useful Improvement in Adding-Machines, of which the following is a specification.

My invention relates to multiple-order keyboard adding-machines, and is herein particularly shown as embodied in a multiple-order key-driven duplexing calculating-machine, the well-known comptometer set forth in such prior Felt patents as Nos. 762,520, 762,521 of June 29, 1904; 767,107 of August 9, 1904; 960,528 of June 7, 1910; and 996,009 of June 20, 1911.

The invention has for an object the special adapting of such adding-machines to direct additive computations involving the use of common fractions of high denominator values. And the invention has for further objects such other improvements in structure or function as may be found to obtain in the devices hereinafter described or claimed.

In the accompanying drawings, forming a part of this specification, Figure 1 is a top plan view of the keyboard of a comptometer adapted to embody my invention; Fig. 2 is a section on the line 2—2 of Fig. 1; Fig. 3 is a section on the line 3—3 of Fig. 1; Fig. 4 is a section on the line 4—4 of Fig. 1; Fig. 5 is a diagram of the notation on the rim of the lower or right-hand of the two fractional numeral-wheels; Fig. 6 is a like diagram of the higher or left-hand of said fractional numeral-wheels; Fig. 7 is an enlarged detail side view of one of the usual carrying-cams that impart carrying movements to the ordinary decimal numeral-wheels; Fig. 8 is a like view of the special carrying-cam for imparting to the higher of the two fractional numeral-wheels carrying movements that are each greater than one-tenth of a rotation; Fig. 9 is an enlarged side view of the carrying lever of usual form that coacts with the carrying-cam in each decimal order of the machine;

and Fig. 10 is a like view of the special carrying-lever that coacts with the special carrying-cam shown in Fig. 8.

Like reference numerals indicate like parts in all the figures.

In machines of this character the requirements of high speed and lightness of action and uniformity of key-touch impose limitations upon the size and weight of the numeral wheels and the devices that immediately control them, and consequently it has been found impracticable to subdivide the numeral-wheels into more than about ten or twelve reading spaces, or to have them actuated less than about one-tenth or one-twelfth of a rotation at any one impulse. As a result of this condition, it has not been practicable to so arrange the numeral wheels and their actuating mechanism as to provide for the direct addition of common fractions of a denominator value greater than, or an actual value less than, about tenths or twelfths of unity. But by my present invention, I am able conveniently to effect additive computations involving common fractions having far greater denominators without need for materially increasing the number of reading spaces on the numeral wheels or materially reducing the length of the shortest movement they may be required to make in response to any one actuating impulse. This is accomplished by employing a plurality of mutually adjacent numeral wheels, transferring from one to another and all bearing common fractions of one common denominator value equal to one more than the sum of the respective highest numerator values on said wheels, but with the numerator values on the higher or left-hand wheel in multiple of or exceeding the numerator values on the next lower or right-hand wheel, and by providing keys determining the adding movements of these numeral wheels and designating corresponding fractional values. The common denominator value will be at least one more than the total number of mutually different significant readings on all said wheels. Such

of the fractions as can be reduced to lower terms may, if desired, have their numerator and denominator values so expressed on either the keys or the wheels or both,—for instance, $4/32$ may be expressed as $\frac{1}{8}$, which, though reduced to lower terms, leaves the numerator and denominator values the same as in $4/32$.

In the particular embodiment of my invention illustrated in the annexed drawings, I have shown a pair of numeral-wheels, and corresponding keys, for effecting the adding of thirty-seconds, although neither numeral-wheel is subdivided into more than eight 15 reading spaces or has a minimum one-step movement of less than one-eighth of a rotation. But, for instance, by the employment of a pair of wheels each subdivided into twelve readings (eleven significant and one 20 blank), and each having a corresponding series of eleven actuating keys, and with said wheels and keys all bearing common fractions of one common denominator value, I would be able to effect the direct addition of 25 fractions of as high a denominator value, or as small an actual value, as one-hundred-and-forty-fourths, giving a minimum adding capacity of $1/144$, and a maximum fractional addition, at one operation, of $143/144$. 30 Fractions having still greater common denominator values may be handled either by further subdividing the wheels into a greater number of readings or by employing more than two of the fractional wheels. And one 35 of the fractional wheels may be provided with an alternating repetition of one fraction and a blank, and arranged to carry at each alternate one-step movement, so that it may be controlled either by one key near- 40 ing the same fraction that it registers, or by a series of keys including the same fraction that it registers and the successively higher values registerable through the plurality of carryings imparted to the next higher order 45 in each rotation of such wheel,—for instance, to illustrate the wide range of possibilities thus opened up:—employing two wheels each having twelve readings, the left-hand wheel might register “ $2/24$,” “ $4/24$,” “ $6/24$,” “ $8/24$,” “ $10/24$,” “ $12/24$,” “ $14/24$,” “ $16/24$,” “ $18/24$,” “ $20/24$,” “ $22/24$,” and a 50 blank, and have eleven keys bearing corresponding significant readings, while the right-hand or lower wheel would show six repetitions of “ $1/24$ ” alternating with six blanks, and carry at each alternate one-step advance, and either have only a key marked “ $1/24$ ” or a series of keys marked “ $1/24$,” “ $3/24$,” “ $5/24$ ” and “ $7/24$ ”; or the left- 55 hand wheel might show six repetitions of “ $12/24$ ” alternating with six blanks, and carry a whole unit to the next higher wheel at each alternate one-step advance and have only a key marked “ $12/24$ ” while the right- 60

hand or lower fractional wheel would register “ $1/24$,” “ $2/24$,” “ $3/24$,” “ $4/24$,” “ $5/24$,” “ $6/24$,” “ $7/24$,” “ $8/24$,” “ $9/24$,” “ $10/24$,” “ $11/24$,” and a blank, and have eleven keys bearing corresponding significant readings. These last several examples, particularly 70 illustrate the possibilities of employing a small number of keys for making direct computations in common fractions of high denominator values.

In the plan view shown in the drawings, 75 it will be observed that the fractional keys, as well as the corresponding numeral-wheels, bear common fractions all having thirty-seconds as denominators, and that the right-hand or lower series of such fractional 80 keys, and the corresponding numeral wheel, bear numerator values of, respectively, “1,” “2” and “3,” while the numerator values on the next higher or left-hand series or order of keys, and its corresponding numeral wheel, are, respectively, “4,” “8,” “12,” “16,” “20,” “24” and “28.” Any 85 number of thirty-seconds, less than unity, can be immediately added, either by striking the key bearing the required numerator, 90 if such numerator appears on any one key in either of the two fractional orders, or else by striking two keys the sum of whose numerators equal the required numerator. For instance, $2/32$ can be registered by simply 95 striking the key so marked in the lower or right-hand fractional column; or $20/32$ can be registered by simply striking the key so marked in the higher or left-hand fractional column; and $7/32$ can be registered by 100 simply striking simultaneously or successively the keys respectively marked “ $4/32$ ” and “ $3/32$.” In similar manner the result 105 is read from the two fractional numeral-wheels by simply summing the two numerators that appear in the sight openings, the denominators being the same on both of said fractional wheels. Such sum will always be less than unity.

20 is the lower or right-hand fractional 110 numeral-wheel, having prime actuating-and-controlling mechanism of the ordinary form employed in adding quarters, and it bears four readings, namely, “ $1/32$,” “ $2/32$,” “ $3/32$ ” and a blank, said readings 115 being spaced 90 degrees apart.

21 is the higher or left-hand fractional 120 numeral-wheel, having its prime actuating-and-controlling devices of the ordinary form employed in the adding of eighths, and bearing eight readings, namely, “ $4/32$,” “ $8/32$,” “ $12/32$,” “ $16/32$,” “ $20/32$,” “ $24/32$,” “ $28/32$ ” and a blank, said readings being spaced 45 degrees apart.

22, 22, are the higher numeral-wheels of 125 the ordinary form and having the ordinary actuating mechanism for the adding of the integers of decimal notation.

23 is the column actuator driven by the keys 24, 24, for actuating the aforesaid lower or right-hand fractional numeral wheel 20.

25 is the column actuator driven by the keys 26, 26, for actuating the higher or left-hand fractional numeral-wheel 21.

27, 27 are the column actuators driven by the keys 28, 28, for actuating the integer-bearing numeral-wheels 22, 22.

10 In the particular arrangement of fractional notation shown in the accompanying drawings, the relations of the numerator values in the two fractional columns are such as to require that the left-hand or 15 higher of the two fractional wheels shall have a minimum movement, at any one impulse, of one-eighth of a rotation; and this is a greater angular movement than has ordinarily been imparted by any impulse 20 of a carrying mechanism in machines of this character, the usual movement imparted by an impulse of the carrying mechanism being only a one-tenth, or even less part, of a rotation of the carried numeral wheel.

25 (The usual carrying mechanism is familiarly exemplified in the well-known duplex comptometers that are particularly described, as to said feature, in the Felt Patents 762,520, 762,521 and 996,009, the last 30 named recent Felt patent, issued June 20, 1911, discussing especially the operation of the carrying mechanism parts whose further changes are here next mentioned.) To enable the carrying mechanism actuated by 35 the lower or right-hand fractional numeral-wheel to impart to the higher or left-hand fractional numeral-wheel the aforesaid greater movement of $\frac{1}{8}$ of a rotation of said higher wheel, it has been necessary to provide that the carrying lever shall have a 40 greater amplitude of movement than in the case of the carrying levers that impart carrying impulses to the higher wheels that bear the integers of the ordinary decimal 45 notation. To effect this greater movement of this particular carrying lever, the carrying cam 29 that impels it is recessed, at 30, more deeply than is the case in the ordinary carrying cams 31, such as are employed in 50 the carrying mechanism in the higher orders of the machine. And this deeper recessing in the said carrying cam 29 accommodates a larger dolly roll, 32, on the special carrying lever, 33, as compared with the dolly roll 34 55 on the ordinary form of carrying lever 35. The greater radius of this dolly-roll of course gives the carrying-lever a throw of greater amplitude when the said roll rides over the cam. The special carrying lever 33 60 is also provided with a carrying pawl, 36, that is so formed as to be longer than the carrying pawl 37 on the ordinary carrying lever 35. This increased length of the carrying-pawl enables the pawl to impart to

its wheel the throw of greater amplitude 65 that the larger dolly-roll gives to the carrying-lever that bears said pawl. The body of the special carrying lever, 33, is also shaped out, at 38, to accommodate the action of the larger dolly-roll 32. Through 70 these special changes it becomes possible to handle common fractions whose large denominator values and particular numerator values are in such relation as to require the use of a higher or left-hand fractional 75 numeral-wheel that has a minimum possible movement greater than one-tenth of a rotation. But in many possible combinations of fractional wheels for handling common fractions of high denominator value, some 80 examples of which have been hereinabove mentioned, no such modification of the carrying devices is required.

For the purpose of performing subtraction and other negative computations, by the 85 usual processes of complemental addition, it is only necessary that the fractional keys shall also bear negative markings analogous to the co-digits marked on the keys used for the addition of integers. The negative 90 marking on any one of these fractional keys would in every instance be a fraction having the same denominator value as the positive marking on the same key, but having a numerator value equal to the difference between the positive numerator value on the same key and the greatest numerator value in the same column of keys. For instance, in the machine shown in the drawings, the negative marking on the key whose positive 100 marking is "1/32" would be "2/32;" and the negative marking on the key whose positive marking is "8/32" would be "20/32." These negative markings would, as usual, be distinguished from the positive markings 105 by being in smaller figures and, preferably, in a distinguishing color. In subtracting by means of such negative markings,—if the fraction to be subtracted were the same as any one of the positive key-markings, the 110 operator would touch the key having a negative marking of next lower value, in the same column of keys; but if the fraction to be subtracted were one of a numerator value not appearing in and less than any positive 115 marking on the keys, then the operator would touch the key having the next lower value in negative marking in the left-hand of the two columns of fractional keys and also touch in the right-hand column the key 120 whose negative marking is next lower in value than the difference between the fraction to be subtracted and the negative marking on the aforesaid key touched in the left-hand column; or if the proper fraction to 125 be subtracted were one of a numerator value greater than any positive marking on the keys, then the operator would touch only the

negative marking; in the right-hand column, that is of next lower value than the difference between the fraction to be subtracted and highest positive marking in the left-hand column.

5 The usual subtraction rules would be followed as to using the subtraction levers to intercept the false carry; and also as to touching the topmost key in columns to the left of the keys used for registering the subtracted fraction, in any instance where the registration standing on the corresponding wheels happened to be less than the amount to be subtracted. For instance, in the machine shown in the drawings, if the right-hand fractional wheel read "3/32" and the left-hand fractional wheel "28/32" and it were desired to subtract "1/32" the operator would strike the key in the right-hand column having the negative value "0/32" (which would be the key having the positive reading "3/32"); or were it desired to subtract "4/32," the operator would strike the key in the left-hand fractional column having the negative value "0/32" (which would be the key having the positive reading "28/32"); or were it desired to subtract "5/32," the operator would strike the key in the left-hand column having the negative value "4/32" (which would be the key having the positive reading "24/32") and also strike the key in the right-hand column having the negative value "0/32" (which would be the key having the positive reading "3/32"); or were it desired to subtract "29/32," the operator would strike only the key in the right-hand column having the negative marking "0/32" (which would be the key having the positive reading "3/32"). And 40 always the operator would hold pressed the subtraction lever just to the left of so much of the register reading as is large enough to contain the subtrahend; and if the amount standing on the fractional wheels were less than the subtrahend fraction, the operator would not only strike the keys specified in the examples just given but would also strike the topmost key in each column to the left until reaching the point at which the said 45 subtraction lever is held pressed.

50 While I have above set forth a particular illustrative embodiment of my invention, it will be understood that the said invention is capable of being embodied in widely various forms and methods of application, and I do not wish to limit it to less than all the possible variations that may be included within the here following statement of claim.

60 I claim:

1. In a multiple-order keyboard adding-machine, in combination: a plurality of ordinal series of keys designating integers; and a plurality of series of keys all designating common fractions of one common

denominator value, a left-hand series of said fractional keys designating fractions having numerator values that are progressive multiples of the other numerator values of the fractions designated by the next adjacent right-hand series of keys; substantially as specified. 70

2. In a multiple-order keyboard adding-machine, in combination: a plurality of orders of keys designating integers; and a plurality of orders of keys all designating common fractions of one common denominator value, a left-hand order of said fractional keys designating fractions having a numerator value in multiple of the numerator value of fractions designated by the next adjacent right-hand order of the keys; substantially as specified. 75

80 3. In a multiple-order key-driven calculating-machine, in combination: adding-mechanism including numeral-wheels and transfer devices adapted to permit said adding-mechanism to receive prime key-actuations in a plurality of orders simultaneously; a plurality of orders of keys designating integers; and a plurality of orders of keys all designating common fractions of one common denominator value, a left-hand order of said fractional keys designating fractions having a numerator value in multiple of the numerator value of fractions designated by the next adjacent right-hand order of the keys, the transfer devices between the fractional orders being adapted to impart numeral-wheel movements of the special amplitude required by the fractional values to be transferred; substantially as specified. 90

95 4. In a multiple-order key-driven calculating-machine, in combination: adding-mechanism including numeral-wheels and transfer devices adapted to permit said adding-mechanism to receive prime key-actuations in a plurality of orders simultaneously, one of said transfer devices being further adapted to impart to the next higher numeral-wheel a proper transfer-movement exceeding one-tenth of a rotation and registering a fractional value greater than one-tenth of unity; a plurality of ordinal series 100 of keys designating the integers of a decimal notation; and a plurality of series of keys all designating common fractions of one common denominator value, a left-hand series of less than nine of said fractional keys designating fractions having numerator values that are multiples of the other numerator values of the fractions designated by the next adjacent right-hand series of keys; substantially as specified. 110

115 5. In a multiple-order keyboard adding-machine, in combination: adding-mechanism including a series of numeral-wheels and transfer-mechanism therefor, one set of said numeral-wheels designating integers, and 120

125 6. In a multiple-order keyboard adding-machine, in combination: a plurality of orders of keys designating integers; and a plurality of orders of keys all designating common fractions of one common

- another set designating fractions all of one common denominator value, a left-hand one of said fractional wheels designating fractions having numerator values that are 5 multiples of the other numerator values of the fractions designated by the next adjacent right-hand numeral-wheel; and keys co-operating with and determining the adding movements of the numeral-wheels, and 10 designating corresponding integers and fractional values; substantially as specified.
6. In a multiple-order keyboard adding-machine, in combination: a plurality of ordinary column-actuators having keys designating integers; and a plurality of column-actuators having keys all designating common fractions of one common denominator value, a left-hand one of said fractional column-actuators registering fractions having 15 a numerator value in multiple of the numerator value of fractions registered by the next adjacent right-hand column-actuator; substantially as specified.
7. In a multiple-order keyboard adding-machine, in combination: adding-mechanism including a series of numeral-wheels and transfer-mechanism therefor, one set of said numeral-wheels designating integers, and another set designating fractions all of 20 one common denominator value, a left-hand one of said fractional wheels registering fractions having a numerator value in multiple of the numerator value of fractions registered by the next adjacent right-hand numeral-wheel; and keys co-operating with and determining the adding movements of the numeral-wheels, and designating corresponding integers and fractional values; substantially as specified.
8. In a multiple-order keyboard adding-machine, in combination: adding-mechanism including a series of numeral-wheels and transfer-mechanism therefor, one set of said numeral-wheels designating integers, and another set designating fractions all of one common denominator value equaling one 25 more than the sum of the respective highest numerator values designated by said fractional wheels, a left-hand one of said fractional wheels registering fractions having a numerator value in multiple of the numerator value of fractions registered by the next adjacent right-hand numeral-wheel; and keys co-operating with and determining the adding movements of the numeral-wheels, and designating corresponding integers and fractional values; substantially as specified.
9. In an adding-machine, in combination: adding-mechanism including a series of numeral-wheels and transfer-mechanism therefor, one set of said numeral-wheels designating integers, and another set designating common fractions, a left-hand one of said fractional wheels registering common fractions of higher value than, but readable as 30
- one common fraction with, the registrations of the next adjacent right-hand fractional numeral wheel, said right-hand wheel transferring its accumulated lower fractional values to the higher fractional values on 70 said left-hand wheel; and manipulative devices for determining the registrations of said fractional wheels; substantially as specified.
10. In a multiple-order keyboard calculating-machine, in combination: a plurality of orders of keys designating integers; and a plurality of orders of keys all designating common fractions of one common denominator value, a left-hand order of said fractional keys designating fractions having a numerator value in multiple of the numerator value of fractions designated by the next adjacent right-hand order of the keys; the fractional keys also bearing negative markings adapting them to subtractive computations, the negative marking on each such key being equivalent to the difference between the positive fractional marking of the same key and the highest fractional marking 80 designated in the same order of keys; substantially as specified.
11. In a multiple-order keyboard adding-machine, in combination: adding-mechanism including a series of numeral-wheels and transfer-mechanism therefor, one set of said numeral-wheels designating integers, and another set designating fractions all of one common denominator value, a left-hand one of said fractional wheels designating fractions having numerator values that are multiples of the other numerator values of the fractions designated by the next adjacent right-hand numeral-wheel; and keys co-operating with and determining the adding 90 movements of the numeral-wheels, and designating corresponding integers and fractional values; the numerators of the fractions on the keys which co-operate with the said right-hand fractional wheel being prime; substantially as specified.
12. In a multiple-order keyboard adding-machine, in combination: a plurality of ordinary column-actuators having keys designating integers; and a plurality of column-actuators having keys all designating common fractions of one common denominator value, a left-hand one of said fractional column-actuators registering fractions having a numerator value in multiple of the 100 numerator value of fractions registered by the next adjacent right-hand column-actuator; the numerators of the fractions on the keys which co-operate with the said right-hand column-actuator being prime; substantially as specified.
13. In a multiple-order keyboard adding machine, in combination: a plurality of series of keys all designating common fractions of one common denominator value, 110
- 120
- 125
- 130

comprising a series of keys the numerators of whose value designations differ progressively by a certain number, and comprising another series of keys the numerators of 5 whose value designations differ from each other progressively by units and extend from unity to one less than the said certain number; and means by which each of said 10 keys registers the value of its designations; whereby all of the possible numerators of

said denominator may be registered by a relatively small number of keys; substantially as specified.

In witness whereof, I have hereunto set my hand in the presence of two subscribing 15 witnesses.

GEORGE STENINGER BOLLESEN.
